(57) **CLAIM**

The ornamental design for a light emitting handle, as shown and described.

DESCRIPTION

FIG. 1 is a top perspective view of a light emitting handle showing the new design;

FIG. 2 is a bottom perspective view thereof;

FIG. 3 is a front side elevation view thereof;

FIG. 4 is a back side elevation view thereof;

FIG. 5 is a left side elevation view thereof;

FIG. 6 is a right side elevation view thereof;

FIG. 7 is a top view thereof; and,

FIG. 8 is a bottom view thereof.

The dash-dot-dash lines in the figures illustrate portions of the environment and form no part of the claimed design. The dash lines in the figures illustrate portions of the design that form no part of the claimed design.
